UNITED STATES PATENT OFFICE

162,549

FIGURINE OR SIMILAR ARTICLE

Reinhold H. Lenaburg, Pasadena, Calif.

Application March 11, 1949, Serial No. 1,349

Term of patent 3½ years

(Cl. D29—23)

To all whom it may concern:

Be it known that I, Reinhold H. Lenaburg, a citizen of the United States and residing at Pasadena, in the county of Los Angeles and State of California, have invented a new, original, and ornamental Design for a Figurine or Similar Article, of which the following is a specification, reference being had to the accompanying drawings, forming part hereof.

Figure 1 is a view in front perspective of a figurine or similar article embodying my new design;

I claim:

The ornamental design for a figurine or similar article, substantially as shown.

REINHOLD H. LENABURG.
